US00D970132S

(12) **United States Design Patent** (10) **Patent No.:** **US D970,132 S**
Chen (45) **Date of Patent:** **** Nov. 15, 2022**

(54) **VACUUM CLEANER**

(71) Applicant: **SHENZHEN JUNENG VEHICLE TECHNOLOGY CO., LTD.**, Shenzhen (CN)

(72) Inventor: **Longlin Chen**, Shenzhen (CN)

(73) Assignee: **SHENZHEN JUNENG VEHICLE TECHNOLOGY CO., LTD.**, Shenzhen (CN)

(**) Term: **15 Years**

(21) Appl. No.: **29/778,881**

(22) Filed: **Apr. 15, 2021**

(30) **Foreign Application Priority Data**

Feb. 4, 2021 (CN) 202130082654.4

(51) **LOC (13) Cl.** **15-05**
(52) **U.S. Cl.**

USPC **D32/18**

(57) **CLAIM**

The ornamental design for a vacuum cleaner, as shown and described.

DESCRIPTION

FIG. 1 is a side perspective view of the new design of a vacuum cleaner;

FIG. 2 is another side perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top view thereof; and,

FIG. 8 is a bottom view thereof.

The broken (dashed) lines show portions of the vacuum cleaner that form no part of the claimed design.

1 Claim, 8 Drawing Sheets
